UNITED STATES PATENT OFFICE

156,688

SUPPORTING STAND FOR MOTOR-DRIVEN FOOD APPLIANCES OR SIMILAR ARTI- CLES

Marvin E. Allesee, Chicago, Ill., assignor to Dormeyer Corporation, Chicago, Ill., a corporation of Illinois

Application April 23, 1947, Serial No. 138,552

Term of patent 14 years

(Cl. D44--1)

To all whom it may concern:

Be it known that I, Marvin E. Allesee, a citizen of the United States, residing at 30 North Lavergne Avenue, in the city of Chicago, county of Cook and State of Illinois, have invented a new, original, and ornamental Design for Supporting Stands for Motor Driven Food Appliances or Similar Articles, of which the following is a specification, reference being had to the accompanying drawings, forming a part thereof.

Fig. 1 is a view in side elevation and partly in section of a supporting stand for motor driven food appliances or similar articles, embodying my new design;

Fig. 2 is a top plan view;

Fig. 3 is a front elevational view; and

Fig. 4 is a bottom plan view thereof.

The dominant features of my design reside in the portions shown in solid lines.

I claim:

The ornamental design for a supporting stand for motor driven food appliances or similar articles, as shown and described.

MARVIN E. ALLESEE.
